UNITED STATES PATENT OFFICE.

WILLIAM B. CARGAL AND WINSTON TANKERSLEY, OF DALTON, GEORGIA.

BOBBIN-BEARING.

1,265,995.

Specification of Letters Patent. Patented May 14, 1918.

Application filed March 1, 1918. Serial No. 219,908.

To all whom it may concern:

Be it known that we, WILLIAM B. CARGAL and WINSTON TANKERSLEY, citizens of the United States, residing at Dalton, in the county of Whitfield and State of Georgia, have invented certain new and useful Improvements in Bobbin-Bearings; and we do declare the following to be a full, clear, and exact description of the invention, such as will enable others skilled in the art to which it appertains to make and use the same.

Our invention aims to provide a simple and inexpensive, yet a highly efficient, durable and easy running bearing for the bobbins of spinning frames and analogous machines, the device being so constructed as to form a mounting for the lower end of an upper bobbin and the upper end of a lower bobbin.

With the foregoing general object in view, the invention resides in the novel features of construction to be hereinafter fully described and claimed, the descriptive matter being supplemented by the accompanying drawing which forms a part of this specification and in which:

Figure 1 is a side elevation of the invention applied, the bobbin being in operative position;

Fig. 2 is a vertical longitudinal section through the parts seen in Fig. 1; and

Fig. 3 is a side elevation partly in section showing the manner in which the bobbin is removed.

In the drawing above briefly described, the numeral 1 designates a cylindrical head of uniform size throughout, the lower end of said head having an integral cylindrical neck 2 depending centrally therefrom, the lower end of said neck being formed with a central vertical bearing stem 3 upon which a cone 4 is slidable and rotatable for reception in the upper end of one of the bobbins B, a screw 4' being threaded into the lower end of the stem to retain the cone thereon when the bobbin is removed. The parts 1, 2 and 3 are turned from a single length of metal and the lower end portion of the neck 3 is externally threaded for reception in a nut 5 which coacts with the head 1 in clamping the device in place; after said neck has been passed through an opening in the frame 6.

The upper end of the head 1 is recessed to form a circular socket 7 having a ball race 8 at its bottom, and said head and the neck

2 are formed with a central vertical bore 9 whose lower end is closed, while its upper end opens into the socket. A cylindrical plug 10 above the head 1 is adapted for reception in the lower end of the bobbin as shown clearly in Fig. 2, said plug having a bobbin supporting flange 11, a depending guard flange 12 surrounding the upper end of the head 1, and an integral central cone 13 received in the socket 7 and resting on ball bearings 14 which are received in the race 8. The pointed lower end of the cone 13 is provided with an integral spindle 15 whose lower end is pointed at 16 and rests upon the closed lower end of the bore 9. Between its ends, the spindle 15 is provided with an annular groove 17 and the inner end of a screw 18 is received in said groove to prevent removal of the spindle from the bore, 2 as seen in Fig. 2.

On spinning frames and similar machines, three vertically spaced series of bobbins are usually provided, and the present invention is adapted for use between the upper and lower series and the central series, the cones 4 being received in the upper ends of the bobbins while the plugs 10 project into the lower ends thereof. For the upper ends of the upper series of bobbins stems such as 3 and cones 4 are provided without the additional features of the bearing, while for the lower end of the lower series of bobbins, all features of the device are used except the stems and cones in question. The device is obviously of simple and inexpensive nature, yet it provides an efficient anti-friction bearing for the bobbins and permits quick application and removal of the latter as occasion may demand. Since probably the best results are obtained from the exact features shown and described, these features are preferably employed, but within the scope of the invention as claimed, numerous minor changes may well be made.

We claim:

A bobbin bearing comprising a cylindrical metal head having a cylindrical central neck formed integrally with its lower end, the lower end of said neck having formed integrally therewith a central vertical bearing stem, the upper end of said head having a circular socket formed at its bottom with a ball race, said head and neck having a central bore closed at its lower end and opening at its upper end into said socket, ball bear-

ings in said race, a metal plug for reception in the bobbin, a cone integral with said plug and received in said socket on said ball bearings, a spindle integral with said cone and received in said bore, said spindle having a pointed lower end resting on the closed lower end of said bore, a second cone slideable and rotatable on the aforesaid bearing stem, a stop for retaining said second cone 10 on said stem when the bobbin is removed, and a nut threaded on said stem for coaction

with said head in securing the device in place.

In testimony whereof we have hereunto set our hands in the presence of two sub- 15 scribing witnesses.

WILLIAM B. CARGAL.
WINSTON TANKERSLEY.
